US00D854044S

(12) **United States Design Patent** (10) Patent No.: **US D854,044 S**
(45) Date of Patent: **** Jul. 16, 2019**

(54) **COMPUTER DISPLAY SCREEN WITH
GRAPHICAL USER INTERFACE FOR
LIGHTING**

- (71) Applicant: **Seasonal Specialties, LLC**, Eden Prairie, MN (US)
- (72) Inventors: **Tim Hess**, St. Louis Park, MN (US); **Christine Werner**, St. Louis Park, MN (US); **Steven Altamura**, Scarsdale, NY (US); **Derek Anderson**, Blaine, MN (US)
- (73) Assignee: **Seasonal Specialties, LLC**, Eden Prairie, MN (US)

(**) Term: **15 Years**

(21) Appl. No.: **29/618,518**

(22) Filed: **Sep. 21, 2017**

Related U.S. Application Data

(62) Division of application No. 29/600,099, filed on Apr. 10, 2017, now Pat. No. Des. 800,758, which is a division of application No. 29/503,069, filed on Sep. 23, 2014, now abandoned.

(51) LOC (11) Cl. **14-04**

(52) U.S. Cl.

USPC **D14/488**
